LEANDER D. HARTER ^{Inventor}

By Herman A. Phillips

Attorney

UNITED STATES PATENT OFFICE.

LEANDER DOUGLAS HARTER, OF ARANSAS PASS, TEXAS.

CONCRETE TILE FOR BUILDING CONSTRUCTION.

1,086,821.

Specification of Letters Patent. Patented Feb. 10, 1914.

Application filed May 14, 1913. Serial No. 767,626.

To all whom it may concern:

Be it known that I, LEANDER DOUGLAS HARTER, a citizen of the United States, residing at Aransas Pass, in the county of San Patricio and State of Texas, have invented certain new and useful Improvements in Concrete Tiles for Building Construction, of which the following is a specification.

13. My invention relates to improvements in concrete tiles for building construction, designed especially for use in building walls, partitions, ceilings, etc. of building structures.
15. The primary object of the invention is the provision of a building-tile of concrete for the construction of walls, which will be comparatively inexpensive of production and in the cost of material. By the utilization 20 of the building-tiles a wall may be erected with greater rapidity than customary, and with much facility, and by the equipment of my special securing devices, the liability of cracking or breaking the tile is reduced to a minimum. The walls, in addition to being erected with facility, may also be dismantled with equal facility, without marring or destroying the tiles, and the same 25 may be used a second time when desired.
30. My invention consists in certain novel features of construction and combinations and arrangements of parts as hereinafter described and claimed.

In the accompanying drawings I have 35 illustrated one complete example of the physical embodiment of my invention constructed according to the best mode I have so far devised for the practical application of the principles.

40. In the drawings: Figure 1 shows a wall, partly completed, and in perspective, built according to, and embodying the novel features of my invention. Fig. 2 is an enlarged detail perspective view of a tile built according to my invention. Fig. 3 is a detail perspective view showing the metallic frame work upon which the concrete tile is built. Fig. 4 is a vertical transverse sectional view through the metallic frame of 45 a tile. Fig. 5 is an enlarged view showing an additional form of sleeve by which the tiles are bolted to the frame upright.

In the preferred embodiment of my invention I employ concrete tiles that are 50 made of suitable and customary material,

and molded in a machine for the purpose, and of uniform size and shape. These tiles are built upon a metallic frame made of channel iron designated as a whole by the numeral 2. The rectangular frame includes 55 an end and bottom bar 2', an end and top bars 3—3 which provide a tongue and groove connection (see Fig. 4). Between the four bars of the frame a wire mesh 4 is secured and at suitable locations on the frame, preferably at the four corners thereof, I provide a sleeve or ferrule 5. These ferrules are fixed in suitable manner to the frame bars 2' or 3 and extend transversely of the frame with their ends projecting beyond the 60 two sides of the frame. These ferrules accommodate securing bolts 6 which, by means of nuts 7, are secured to the upright I-beams 8 used in a house frame. The bolts are adapted to pass through the sleeves 5 and are then passed through perforations bored in the uprights 8, and by means of the nuts 7 are secured in position.

In Fig. 2, countersinks 9 are shown in the concrete material of the tiles 1, and these 65 are provided so that after the bolt 6 has been passed through the sleeve 5 and secured to the upright this countersunk opening may be plastered or cemented up to eliminate the hole and make a flush and 70 smooth surface over the bolt head. In Fig. 5, another form of sleeve is indicated at 10, and this sleeve is embedded in the concrete tile 7 and has a pair of lugs 11 projecting diametrically from the sleeve to hold the 75 sleeve against turning in the concrete after the latter has dried.

In the structure that is illustrated as in course of erection in Fig. 1, the outer wall of a building is shown and the tiles are attached to the uprights 8 by the bolts. As 80 shown in Fig. 4, it will be seen that the frame bars 2' provide a concave channel around two sides of the tile, and it will be understood that the smaller channel iron bars 3 of the frame are adapted to fit in the 85 groove or channel of the frame bars 2'. In this manner the bars 2' of the frame of a block are fitted over the bar 3 of the lower tile when the wall of the building is being 90 erected, and the blocks are thus interlocked by the connection between the bars 2' and 3, and displacement of the tile is impossible. The sleeves are preferably in the form of 95 pipe sections and are held securely in the 100 105 110

metallic frame as shown in Fig. 3, but in some instances it may be necessary to employ the sleeve in a position where it is inconvenient or undesirable to attach it to the metallic frame and in such case the sleeve 10 with its lugs 11 is employed. By the use of this sleeve 10 the tile may be fastened or secured by the bolt 6 as desired, and the lugs 11 which are securely embedded in the concrete material prevent turning of the sleeves. In the process of erecting a wall according to my invention, the first or lowest course of tile are laid, and in Fig. 1 it will be noted that each alternate tile is attached to a studding. The intermediate tiles are held in place by the interlocking joints. The tile, with its sleeve embedded therein, is located in proper position, and a hole is bored in the studding in alignment with the sleeve so that the bolt may be passed through the sleeve and hole. The nut is then applied at the end of the bolt and the bolt head is drawn tight against the mouth or head of the sleeve. It will be noted that the strain of attaching the bolt to the studding is taken up entirely between the bolt head and sleeve head at one end of the sleeve, and at the other end the sleeve is in direct contact with the studding. This arrangement prevents any strain on the concrete tile, and therefore eliminates the possibility of cracking or breaking the tile. In some instances the bolt may be screwed

home in the studding and the nut eliminated if desired.

From the above description taken in connection with the drawings, it is evident that I have provided a desirable instrumentality for performing the functions set forth as the objects and purposes of my invention.

Having thus fully described my invention, what I claim as new and desire to secure by Letters Patent, is:—

1. The combination in a concrete tile formed on an open metallic frame comprising side and end bars with outer concave faces, and a wire screen located in the frame, of a sleeve extending transversely through the tile and formed with integral diametrically arranged securing lugs.

2. A concrete building tile comprising an open rectangular metallic frame having one end and one side bar formed of channel iron with the grooved face outward, and one end and one side bar of similar formation but of smaller dimension, wire mesh on the frame, and fastening sleeves formed with integral lugs embedded in the concrete.

In testimony whereof I affix my signature in presence of two witnesses.

LEANDER DOUGLAS HARTER.
